UNITED STATES PATENT OFFICE.

LOUIS J. GENETT, OF MARQUETTE, MICHIGAN, ASSIGNOR OF ONE-HALF TO J. M. LONGYEAR, JR., OF MARQUETTE, MICHIGAN.

PISTON-RING COMPRESSOR.

1,414,014.

Specification of Letters Patent. Patented Apr. 25, 1922.

Application filed March 31, 1919. Serial No. 286,331.

To all whom it may concern:

Be it known that I, LOUIS J. GENETT, a citizen of the United States, residing at Marquette, in the county of Marquette and 5 the State of Michigan, have invented certain new and useful Improvements in Piston-Ring Compressors, of which the following is a specification, reference being had to the accompanying drawings, forming a part there- 10 of.

This invention relates to a device for facilitating the insertion of a piston into the cylinder of a pump or engine with its one or more metallic packing rings properly assembled in their respective grooves. It consists of means for temporarily compressing a piston ring to substantially the size of the piston so that the ring will readily enter the cylinder and the invention involves various 15 features and elements of construction as hereinafter described and shown in the drawings, and as indicated by the claims.

In the drawings:

Figure 1 is a plan view of a device embodying this invention, shown with the cover plate removed to disclose certain interior construction.

Figure 2 is an exterior plan view of the device showing the compressor strap in operative position engaging a piston ring.

Figure 3 is a longitudinal vertical section including fragments of a piston and a cylinder to indicate the mode of use of the invention.

In various types of engines and particularly in internal combustion engines, it is common practice to make the pistons slightly loose in their respective cylinders and to form each piston with one or more circumferential grooves in which there is placed a metallic packing ring of substantially circular outline, but split or broken at one point and somewhat elastic, and having a tendency to expand slightly beyond the size of 35 the piston so as to contact yieldingly but firmly with the cylinder wall to form a gas tight joint between the piston and the cylinder. The assembly of the parts is a matter of some difficulty, particularly in a multi- 40 cylinder engine, and obviously involves compressing each piston ring just prior to its entry into the cylinder,—leaving it properly lodged in its groove in the piston and, at the same time, overcoming its expansive tend- 45

ency, sufficiently to fit it into the cylinder 55 wall.

To facilitate this operation, the present device consists in a frame, 1, and a flexible strap, 2, one end of which is merely attached to the frame, while the other end is adjustably secured so that after said strap, 2, has been placed around the piston ring which is to be compressed, the adjusting means may be operated for drawing the strap tight and thus compressing the ring by the desired 60 amount.

As shown in the drawings, the frame, 1, is provided with a handle, 3, and the adjusting means for the strap, 2, consists of a winding drum, 4, carried on a spindle, 5, which is journaled in the frame, 1, at 6, and in a cover plate, 7, at 8, the drum, 4, being housed in a recess, 9, in the frame under said cover plate. A ratchet wheel, 10, is rigidly associated with the winding drum, 4, and a detent dog, 11, is 65 yieldingly pressed into engagement with said ratchet wheel by a spring, 12, for preventing reversal of the winding drum, 4, when it is being rotated in the direction for winding up the strap, 2, and compressing the 70 piston ring.

By means of a finger piece, 13, on the tail of the dog, 11, extending out along the handle, 3, beyond the cover plate, 7, the said dog, 11, may be released to permit reversal of the winding drum, 4, for removing the strap, 2, from the piston ring, or enlarging the loop formed by the strap. Any 75 suitable handle or crank may be provided for the spindle, 5, for rotating the winding drum, 4; the drawing shows a handle member, 14, similar in shape to a clock winding key and secured to the spindle, 5, for this purpose.

The strap, 2, is preferably a metallic ribbon and has one end permanently hitched 80 to the drum, 4, at 15, the strap emerging from the chamber, 9, through a slot, 16, formed in the frame, 1, and closed by the cover plate, 7. Said slot, 16, has a flaring mouth, 17, with one face, 18, suitably rounded 85 to support the ribbon, 2, when it is considerably deflected from the line of the slot, 16, so as to extend tangent to the circle of the piston ring for encompassing the latter. The opposite end of the strap is formed with 90 an enlargement, 19, made by doubling back the strap upon itself in a small loop, and at 95 the other side from the slot, 16, the frame, 1,

100

105

110

is formed with a short slot, 20, and recess, 21, in which the enlargement, 19, on the adjacent portion of the strap may be entered edgewise for anchoring the free end of the strap prior to drawing it tight around the piston ring.

Figure 3 indicates the relation of the parts when the strap, 2, has been drawn tight around a piston ring, A, on a piston, B. The ring, A, being thus compressed to the same diameter as the piston B, and a part of the ring projecting in Figure 3 slightly above the edge of the compressor strap, 2, it is evident that the piston may now be entered in the cylinder, C, until the upper edge of the compressor strap engages the lower edge of the cylinder block, whereupon said strap may be slidably moved down over the piston, B, the ring, A, being by that time in full control of the cylinder wall. This having been done with the uppermost ring on the piston, if there are additional rings, the process can be repeated by first slightly loosening the strap, 2, and causing it to encompass the next ring on the piston, then sliding it longitudinally over the ring as the latter is gradually entered in the cylinder, C. When the piston with all its rings has been entered in the cylinder the device may be removed by disengaging the enlargement, 19, at the free end of the strap, 2, from the recess, 21, and the slot, 20, and thus drawing the strap around the piston and free of said parts.

I claim:

1. A piston ring compressor comprising a frame, a fully rotatable circular winding drum thereon and a flexible loop continuous from end to end, having one end attached to the frame and the other end hitched to the drum so that rotation of the drum will adjust and tighten the loop.

2. A piston ring compressor comprising a frame, a fully rotatable circular winding drum thereon, a flexible loop continuous from end to end having one end attached to the frame and the other end hitched to the drum to permit adjustment in the size of the loop, a ratchet wheel concentric with the drum and attached thereto, and a detent on the frame adapted to engage the ratchet wheel for holding the loop in adjustment.

3. A piston ring compressor comprising a frame, a fully rotatable circular winding drum thereon, and a flexible loop of flat metal ribbon continuous from end to end, having one end hitched to the winding drum and the other end terminating in a single enlargement, said frame having a recess to accommodate said enlargement with a slot leading therefrom for the ribbon, said recess and slot being laterally accessible to the ribbon for detachably anchoring the end of the latter on the frame.

4. A piston ring compressor comprising a frame, a winding drum journaled on said frame with its face against a flat surface thereof, a flat metal ribbon wound on said drum and forming a flexible loop with its outer end engaged with the frame, said drum having a ratchet wheel rigidly associated with it at the opposite side from said flat face of the frame, and of larger diameter than the drum, to serve as a flange therefor to guide said ribbon on the drum, and a detent on the frame for said ratchet wheel.

5. A piston ring compressor comprising a frame with a handle, a winding drum on the frame, and a flexible loop having one end attached to the frame and the other end hitched to the drum for varying the size of said loop, together with a ratchet wheel and a spring-pressed detent mounted on the frame for automatically maintaining the drum in adjustment, and a trip finger extending adjacent the handle for releasing said detent at will.

6. A piston ring compressor comprising a frame with a housing formed therein, a handle projecting therefrom and a cover for the housing; a winding drum having its shaft journaled in said housing and cover and with a ratchet wheel and detent enclosed therein; a flexible metallic band with one end removably attached to the frame outside the housing and the other end hitched to the drum to be wound thereon for varying the size of the loop formed by said band outside the housing.

In testimony whereof, I have hereunto set my hand at Chicago, Illinois, this 26th day of March, A. D. 1919.

LOUIS J. GENETT.
